UNITED STATES PATENT OFFICE.

JOSEPH EUGENE LOCKWOOD, OF DETROIT, MICHIGAN.

ELECTRIC LOCOMOTIVE.

SPECIFICATION forming part of Letters Patent No. 568,779, dated October 6, 1896.

Application filed June 10, 1893. Serial No. 477,230. (No model.)

To all whom it may concern:

Be it known that I, JOSEPH EUGENE LOCKWOOD, a citizen of the United States, residing at Detroit, in the county of Wayne and State 5 of Michigan, have invented certain new and useful Improvements in Electric Locomotives, which are fully set forth in the following specification, reference being had to the accompanying drawings, in which—

10 Figure 1 is a plan view of an apparatus embodying my invention in one form. Fig. 2 is a detail sectional view of the same, taken on the line 2 2 of Fig. 1 and looking in the direction of the arrows. Fig. 3 is a transverse 15 section taken on the line 3 3 of Fig. 1 and looking in the direction of the arrows.

My invention relates to electric locomotives, and more particularly to that class in which the motor and its equipment are mounted on 20 a truck, which, in turn, is mounted on the axles, which serve to drive the locomotive and carry the wheels on which it is supported and travels.

The object of my present invention is to so 25 support the motor and its gearing as to reduce to a minimum the shock to said parts of the mechanism due to obstructions or unevenness of the track, thus preventing any sudden strain on the gearing, while at the 30 same time the truck is allowed the greatest possible flexibility of movement and the weight of the motor and its equipment is distributed in the most advantageous manner.

To these ends my invention consists in certain 35 novel features which I will now proceed to describe, and will then particularly point out in the appended claims.

In the accompanying drawings, A represents the truck-frame, which is preferably 40 rectangular in form and composed of channel beams or other suitable material. This frame is provided with suitable boxes a, in which are mounted the axles B, which carry the wheels b, on which the locomotive is supported 45 and travels. These boxes a are desirably spring-boxes of any approved type.

C represents the motor, which is of any approved type and which, along with its associated driving-gear, is mounted in a supplemental-frame D, which latter is supported 50 from the truck-frame A in any suitable man-

ner. The construction and arrangement of this supplemental frame shown in the drawings is that which I prefer to employ. As shown, this frame comprises two channel-bars d, which at their central portions are sufficiently far apart to admit of the mounting of the motor C between them. At this point each of the channel-bars d passes under and is secured to a casting D', to which castings the motor proper is secured and by means of which it is supported. Each of these castings D' is provided with two outwardly-diverging arms d', which extend over the side rails a' of the truck-frame A. A bolt a² extends upward from a shoe A', attached to the side rail a' through a suitable aperture in each arm d', and a spring a³ is interposed between the shoe A' and the arm d', the bolt a² passing through said spring. Above the arm d' there is placed upon said bolt a² a spring a⁴, and above this spring there is mounted on the bolt a washer a⁵ and a suitable nut a⁶ to retain the several parts in position.

Any suitable spring connection may be substituted for that just described, and it will be understood, of course, that a similar construction exists at each of the four points where the supplemental frame is connected with the truck-frame. Under certain circumstances I may deem it desirable to connect the supplemental frame directly to the truck-frame without the interposition of springs.

Those portions of the bars d which pass under and are secured to the castings D' are desirably parallel, and from these points the bars d converge toward each other in each direction until they approach the axles B. Those portions of the bars d which pass underneath the axles B are parallel, and their ends beyond the said axles are connected by transverse bars d². In the construction shown these end bars are not connected with the end rails a' of the truck-frame; but, if desired, they may be connected thereto either by a spring connection or rigidly, as desired.

On each side of the motor proper the supplemental frame D is provided with cross-bars d³, which carry the bearings d⁴ for the motor-shaft c. This latter shaft is provided at each of its ends with a bevel-pinion c',

which meshes with a bevel-gear E, supported and connected in the manner hereinafter described.

F is a sleeve mounted in suitable bearings 5 f, supported by the parallel portions of the bars d of the supplemental frame, which extend under the axle B. The axle B extends loosely through this sleeve F without contacting therewith at any point, and the said 10 sleeve is a split sleeve, as indicated in Fig. 1 of the drawings, in order to permit it to be placed around the axle and removed therefrom without displacing said axle. On the 15 sleeve F is mounted the bevel-gear E, already referred to, the said gear being a split gear, so as to permit it to be readily placed upon and removed from the sleeve F.

On each end of the sleeve F there is mounted or formed a disk F', provided with pins f', projecting outward from the face thereof, two pins being shown in the present instance, although a greater or less number may be employed. Opposite to and at a suitable distance from each of the disks F' there is secured on the axle B a disk B', having similar pins b' extending from its face toward the disk F'. The disks B' are desirably split in the manner indicated or in any other suitable manner, so as to permit their ready application to and removal from the axle B. The pins f' and b' are connected with each other by means of spiral springs b², so that motion imparted to the sleeve F will be transmitted to the axle B through the medium of 30 said springs in an obvious manner.

It will be understood, of course, that the description just given applies to both ends of the truck, the construction being in duplicate, but reversed.

40 It will be noted that the motor and all the gearing connected therewith are mounted on a supplemental frame, which is in turn supported upon the truck-frame in such a manner as to permit a perfectly free movement of 45 the truck-frame in accommodating itself to the unevenness of the track or to any obstructions thereon without transmitting the shock, jar, or vibratory movement due to such causes to the supplemental frame or to the mechanism mounted thereon. Moreover, this construction takes the weight of the motor proper away from the bearings f and transmits it directly to the truck-frame A, where it is distributed to the axle-boxes a. This is obviously 55 advantageous for the reason that these axle-boxes are better fitted for carrying this weight, being close to the wheels or axle-supports, and being easily lubricated and readily accessible for this purpose. A greatly-reduced 60 frictional resistance results from this construction, thus increasing the efficiency of the motor.

The mode of connecting the axle with its driving-gear by means of a sleeve mounted 65 in or upon a separate frame and driving the axle through the medium of spring connections possesses many obvious advantages.

In the first place shocks are not transmitted directly from the wheels and axles to the gearing, and sudden strains on the bevel-gears and bevel-pinions are thus prevented. The bevel-gearing which is employed to transmit the power at right angles is mounted in a supplemental frame in such a way that there can be no possibility of their varying 70 from their proper relative positions, since they are supported independently of the axle, and wear or damage to the said gearing is thus prevented. The axles may be given end play to any reasonable extent, which 75 will greatly facilitate the rounding of curves, and the axles may vary in their angular positions both with respect to each other and with respect to the driving-gear without materially affecting the transmission of power 80 and without straining or damaging the gearing.

It is to be noted that according to my construction the motor-frame has no immediate connection with the axles. It is supported 90 wholly by the truck-frame, and receives only indirect support through the intermediary truck-frame from the said axles. The tubular driving-shafts are mounted in bearings on the motor-frame, and therefore are carried 95 thereby and so, ultimately, by the main frame. There is no dependence placed upon the axles for the support of either the motor-frame or the tubular driving-shafts mounted in bearings thereon. It will be noted also 100 from the description above that the motor and all the driving-gear, up to and including the tubular shafts, are mounted entirely upon this supplemental frame, and so are free from any dependence upon the axles for support, 105 the same as the motor-frame itself.

The motor-frame may yield vertically either bodily, at either end, or either side, but as the motor and driving-gear, as stated above, are mounted wholly upon this motor-frame 110 all such vibrations of the latter will be harmless, so far as disturbing the motor or its driving connections is concerned. The provision is complete for relieving the motor and the driving mechanism from all shock due to 115 the movement of the truck-wheels along the track.

If the main or truck frame is elastically supported on the axles, the supplemental motor-frame may be rigidly connected to the truck-frame and the elastic connection therewith, described above, dispensed with.

Having thus described my invention, what I claim to be new, and desire to secure by Letters Patent, is—

125 1. In an electric locomotive, the truck wheels and axles, in combination with a truck-frame mounted thereon, sleeves surrounding the axles but not in contact therewith, an elastic connection between said sleeves and axles, a supplemental frame separate from and independent of the axles, arranged in the space between the latter, mounted on the truck-frame and connected

at its respective ends with the sleeves, an electric motor mounted wholly on said supplemental frame, and gearing connecting said motor with the sleeves, substantially as described.

5 2. In an electric locomotive, the truck wheels and axles, in combination with a truck-frame mounted thereon, a supplemental frame connected to and elastically supported on the truck-frame and extending from axle to axle, tubular sleeves of greater diameter than the axles surrounding the latter and having bearings in the respective ends of the supplemental frame, elastic connections between said sleeves and the axles, a motor mounted on the supplemental frame, and a driving connection between said motor and the said sleeves, substantially as described.

20 3. In an electric locomotive, a truck-frame separate from the car-body, in combination with a motor-frame also separate from the car-body and constructed independently of the truck-frame but connected to and supported by the latter, revoluble tubular shafts 25 mounted in suitable bearings at the respective ends of the said motor-frame, driving-gears connected to the said shafts, truck-axles passing through the said tubular shafts but not in contact therewith, an elastic or yielding connection between the said axles and the tubular shafts, and an electric motor mounted wholly on the motor-frame and having its armature-shaft provided with gears engaging respectively with the driving-gears on the tubular shafts, substantially as described.

30 4. In an electric locomotive, the truck wheels and axles, in combination with a truck-frame separate from the car-body and mounted on said axles, a motor-frame also 40 separate from the car-body and constructed independently of the truck-frame but arranged in the space between the car-axles and supported by the respective side bars of said truck-frame, tubular sleeves, of greater 45 diameter than the truck-axles, arranged to surround the same without contact therewith and mounted in bearings on the respective ends of the motor-frame, a yielding connection between the said sleeves and axles, a 50 motor mounted wholly on the said motor-frame, and a driving connection between the motor and one or both of said tubular sleeves, substantially as described.

55 5. In an electric locomotive, a truck-frame, in combination with the truck wheels and axles mounted therein, a supplemental motor-frame arranged between the axles and provided with lateral extensions elastically sup-

ported on the respective side bars of the truck-frame, revoluble tubular shafts mounted in 60 bearings at the respective ends of said supplemental frame and surrounding the respective axles but not in contact therewith, elastic connections between the said shafts and their respective axles, gear-wheels mounted 65 on the respective tubular shafts, and an electric motor mounted wholly on said supplemental frame and having its armature-shaft arranged lengthwise of the truck and provided with gears at its ends engaging respectively 70 with the gears of said shafts, substantially as described.

6. In an electric locomotive, the truck-axles, in combination with revoluble tubular shafts, F, inclosing the axles but not in contact therewith, an elastic connection between the axles and their respective shafts, a motor-frame, D, arranged between the axles and connected at its ends to the said tubular shafts by suitable journal-bearings in which the latter may turn, beveled gears, E, secured to the tubular shaft, an electric motor, C, mounted wholly on said frame and having its armature-shaft, c, arranged lengthwise of the truck and beveled gear-pinions, c', fixed on the ends 85 of said armature-shaft and arranged to engage respectively with the beveled gears on the tubular shafts, substantially as described.

7. In an electric locomotive, the wheels and axles and the truck-frame, A, in which they are mounted, in combination with the supplemental frame, D, supporting the motor-gearing, the castings, D', at the sides of said frame connected with the truck-frame, the supporting-springs, a², and the motor, C, 90 mounted on the frame, substantially as described.

8. In an electric locomotive, the truck wheels and axles, in combination with a truck-frame mounted thereon, a supplementary 100 motor-frame connected to said truck-frame, arranged in the space between the axles, independent of the latter and revoluble sleeves independent and outside the motor and inclosing the axles, but not in contact therewith, and mounted in said supplemental frame, an electric motor mounted wholly on 105 said supplemental frame independent of and separated from said axles and sleeves, a driving connection between the motor and said sleeves, and elastic connections between said sleeves and axles, substantially as described.
